UNITED STATES PATENT OFFICE.

JACOB SODERBERG, OF PITTSBURGH, PENNSYLVANIA, ASSIGNOR TO PITTSBURGH PLATE GLASS COMPANY, A CORPORATION OF PENNSYLVANIA.

SURFACING MACHINE.

Application filed May 13, 1924. Serial No. 713,111.

To all whom it may concern:

Be it known that I, JACOB SODERBERG, a citizen of the United States, and a resident of Pittsburgh, in the county of Allegheny and State of Pennsylvania, have made a new and useful invention in Improvements in a Surfacing Machine, of which the following is a specification.

The invention relates to surfacing machines and particularly to grinding machines for use in connection with facing and smoothing plate glass, such as shown in my pending application, Serial No. 593,760, wherein the spindles of the grinding runners are driven and the glass, mounted on cars or tables, is carried beneath the runners of a series of machines. The invention is directed toward the provision of improved means for connecting the runner of the machine to its spindle so as to permit a limited and variable amount of rocking movement of the runner in order to secure the functions and results as hereinafter more fully set forth. One embodiment of the invention is illustrated in the accompanying drawings wherein:

Figure 1 is a plan view of the central portion of a runner equipped with the improved spindle connecting means, but with the shield and hopper (shown in Fig. 2) removed. Fig. 2 is a section, on the line II—II of Fig. 1. Figs. 3 and 4 are sections respectively on the lines III—III and IV—IV of Fig. 1. Fig. 5 is a set of views showing the spindle block, the two lower views being vertical sections at right angles to each other. Fig. 6 comprises two views of the shield employed, the lower view being partially in section and partially in side elevation. Fig. 7 comprises three views of the yoke, the two lower views being sections taken at right angles to each other. And Fig. 8 is a set of detailed views of the sand hopper or box, the two lower views being vertical sections taken at right angles to each other.

Referring to Figs. 1 to 4, 1 is the main runner casting, only the central portion of which is shown. Such casting has a socket 2 at its central portion for receiving the connection between the spindle and the runner, and upon the lower side of the casting is the usual planking 3, to which the runner bars 4 are secured. The lower side of the socket 2 is closed by the plate 5, in-

tegral with the casting 1 and provided with four perforations 6 (Fig. 4) through which a mixture of abrasive and water is supplied as hereinafter explained.

The spindle 7 is mounted for rotation in the fixed framework or casing of the machine, the lower end 8 only of which is shown, and this spindle is driven in any desired manner, such as that illustrated in my application heretofore referred to. A roller bearing is carried by the lower end of the casing and this casing also carries a stuffing box 10 for preventing the lubrication supplied to the bearings from leaking out along the spindle.

The lower end of the spindle fits into the spindle block 11 and is secured therein by means of the key 12. This block is constructed as indicated in Fig. 5 and is provided with a pair of hubs 13, 13 adapted to receive the bearing shafts 14, 14 (Fig. 2) secured against rotation in the yoke 15 by means of the transverse keys 16, 16. The block is also provided with a pair of laterally extending integral lugs 17, 17 in which are mounted the adjustable stop bolts 18, 18 (Figs. 1 and 3). This arrangement provides for the rocking movement of the yoke 15 in one direction with respect to the block 11, the ends of the screws being adapted to engage projections 18^a integral with the yoke 15.

The yoke 15 shown in detail in Fig. 7 surrounds the runner block 11 and is provided with a pair of laterally extending journal members 19, 19 mounted for oscillating movement in the journal boxes 20, 20 mounted in the runner socket 2. This mounting of the yoke provides for the rocking of the runner relative to the spindle 7 in a plane at right angles to the rocking movement of the yoke 15 with respect to the spindle, so that the runner itself is free to rock in both directions, giving it a universal joint support. The laterally extending shafts 14, 14 on which the block 11 is mounted for rocking movement have their ends extended past the sides of the yoke, as indicated in Fig. 2 and carry the stop bolts 21, 21, whose lower ends are adapted to engage the stop plates 22, 22 (Fig. 2), such stop plates being secured to the bottom of the runner socket by means of the bolts 23, 23 (Fig. 1). The two sets of stop bolts 21, 21 and 18, 18 serve to adjustably limit the rocking

movement of the runner in both directions with respect to the spindle 7. It is desirable that the runner should be able to rock with respect to the spindle so that it can 5 accommodate itself to the surface of the glass being surfaced, but this rocking movement should be limited within relatively narrow limits in order to avoid the danger of chipping the glass when the runner is 10 lowered, such as would occur if the runner were inclined at too great an angle when it came into contact with the glass. The use of the stop bolts permits the accurate adjustment of the tilting movement of the 15 runner within the desired limits after the runners have been assembled upon their spindles.

Mounted on the runner above the rocking connections is the hopper or box 24 for 20 receiving the mixture of abrasive and water which is to be used and which is supplied to the cavity 25 (Fig. 4) beneath the runner through the perforations 6. This hopper or box is preferably constructed as indicated 25 in detail in Fig. 8, the construction being such that the hopper performs the additional function of a housing or protector for the rocking yoke and block construction heretofore described. This is accomplished 30 by the provision of the flange 26 fitting the annular surface of the runner surrounding the cavity 2 and held in position by means of the bolts 27. The inner portion of the hopper fits around the runner block 11 as 35 indicated in Fig. 2, the effectiveness of the closure at this point being increased by the use of the washer 28 fitting into a recess at the top of the hopper and resting upon the top surface of the runner block. By 40 this means any accumulation of sand or other dirt in the socket 2 is prevented so that the wearing of the pivotal connections is reduced to a minimum and the stop devices are not interfered with such as would 45 be the case if sand or dirt were permitted to work into the recess 2 and between the stop surfaces.

The runner casting adjacent its central portion is provided with four upstanding 50 tubular members 29 which act as conduits between the hopper cavity and the perforations 6 as indicated in Figs. 4 and 1 and these tubular portions are preferably lined with pieces of rubber tubing 30, such tubing 55 serving to insure a tight connection at the joints 31 between the lower surface of the hopper and the upper ends of the tubular members 29. These rubber linings also serve to eliminate the wear of the abrasive upon 60 the inner surfaces of the tubular members 29. The wear upon rubber, by abrasive is relatively slight as compared with wear by abrasive upon metal and the rubber tubing may be easily replaced from time to 65 time when it is worn out.

A guard is also provided intermediate the lower end of the casing 8 and the upper side of the hopper 24 by the use of the guard or shield 32 shown in detail in Fig. 6. This shield is made in two sections clamped together and provided with a groove 33 which engages a rib at the lower end of the casing 8 as indicated in Fig. 2. The lower end of this guard or casing projects down into the abrasive hopper or box in such manner 70 as to prevent the entrance of any abrasive to the interior of the guard. In this manner every precaution is provided for protecting the parts beneath the hopper from abrasive and other dirt which would tend to reduce the wear of the parts or interfere with their proper functioning. The guard 32 75 also serves a secondary function, in that it acts as a support for the tubes 34 by means of which a mixture of abrasive and water is supplied to the hopper. This support is preferably accomplished by means of the blocks 35 in which the tubes 34 are held by means of the set screws 36. The inner ends 80 of the blocks are provided with stems 37 which project into openings 38 provided in the walls of the shield, such stems being secured in place by means of the set screws 39. The advantages of the structure incident to its compactness, its facility of adjustment and the protection of the wearing parts will readily be apparent to those 85 skilled in the art.

What I claim is:

1. In combination, a vertical spindle, a 100 block in which the lower end of the spindle is mounted, a yoke pivoted to the block for rocking movement about a horizontal axis, a runner pivoted to the yoke for rocking movement about a horizontal axis at right 105 angles to said axis about which the yoke pivots, interengaging stop means on the block and yoke for limiting the rocking movement of the yoke, and other interengaging stop means on the yoke and runner for limiting the rocking movement of the runner.

2. In combination, a vertical spindle, a 110 block in which the lower end of the spindle is mounted, a yoke pivoted to the block for rocking movement about a horizontal axis, a runner pivoted to the yoke for rocking movement about a horizontal axis at right angles to said axis about which the yoke 115 pivots, interengaging adjustable stop means on the block and yoke, including a threaded member for limiting the rocking movement of the yoke, and other interengaging stop means on the yoke and runner, including 120 a threaded member for limiting the rocking movement of the runner.

3. In combination, a vertical spindle, a 125 block in which the lower end of the spindle is mounted, a yoke pivoted to the block for rocking movement about a horizontal axis,

- a runner pivoted to the yoke for rocking movement about a horizontal axis at right angles to said axis about which the yoke pivots, an annular abrasive receiving hopper or box secured to the runner and fitting around the spindle and constituting a housing for the yoke and block, a conduit leading through the yoke from the hopper or box to the lower side of the runner, and a conduit for supplying a mixture of abrasive and water to the hopper. 5
4. In combination, a vertical spindle, a block in which the lower end of the spindle is mounted, a yoke pivoted to the block for rocking movement about a horizontal axis, a runner pivoted to the yoke for rocking movement about a horizontal axis at right angles to said axis about which the yoke pivots, a casing in which the spindle is journaled, an annular abrasive receiving hopper or box secured to the runner and fitting around the spindle and constituting a housing for the yoke and block, a conduit leading through the yoke from the hopper or box 10 to the lower side of the runner, a shield or guard surrounding the spindle intermediate the lower end of said casing and the hopper or box and supported from such casing, and a supply conduit supported upon said shield and positioned so as to discharge 30 into the hopper or box. 15
5. In combination, a vertical spindle, a block in which the lower end of the spindle is mounted, a yoke pivoted to the block for rocking movement about a horizontal axis, a runner pivoted to the yoke for rocking movement about a horizontal axis at right angles to said axis about which the yoke pivots, a casing in which the spindle is journaled, an annular abrasive receiving hopper or box secured to the runner and fitting around the spindle and constituting a housing for the yoke and block, and having a discharge outlet, a tubular member integral with the runner adjacent the center thereof 40 extending up through said yoke to the bottom of the hopper or box and registering with the discharge opening therein, and a lining for said tubular member in the form of a tube of rubber composition. 45
- 50

In testimony whereof, I have hereunto subscribed my name this fifth day of May, 1924.

JACOB SODERBERG.
